FIG. 4.

FIG. 2.

FIG. 1.

FIG. 3.

FIG. 5.

FIG. 1 is a front elevational view of a bottle embodying my new design;

FIG. 2 is a side elevational view as viewed from the left of FIG. 1;

FIG. 3 is a side elevational view as viewed from the right of FIG. 1;

FIG. 4 is a top plan view thereof; and

FIG. 5 is a bottom plan view thereof.

The rear is a mirror image of the front shown in FIG. 1.

The characteristic feature of my design is the applicator which extends outwardly from a top portion of the bottle and with its top edge beyond the end of the cap and the side edge substantially aligned with the side of the bottle all as shown.

I claim:

The ornamental design for a bottle, as shown and described.
